UNITED STATES PATENT OFFICE.

FELIX FRANCIS OGIER, OF BUTTE, MONTANA.

VETERINARY INSTRUMENT.

1,067,368.

Specification of Letters Patent. Patented July 15, 1913.

Application filed December 18, 1911. Serial No. 666,428.

To all whom it may concern:

Be it known that I, FELIX FRANCIS OGIER, a citizen of the United States, residing at Butte, in the county of Silverbow and State 5 of Montana, have invented certain new and useful Improvements in Veterinary Instruments, of which the following is a specification.

This invention relates to veterinary surgical instruments and is primarily directed to that type of instruments which are used for cutting the lampas or the swollen lining of the horse's mouth.

Instruments of this class previously devised have been so constructed as to have the cutting blades projected through a shield. A disadvantage of this construction is that the blades are often projected too far, thereby causing painful and serious cuts 20 in the horse's mouth.

An object of the present invention is to provide a lancet or instrument of the class above set forth, the blade or blades of which may be adjusted or regulated to cut to certain depths, depending upon the size of the lampas.

A further object of the present invention is to so construct the instrument whereby after use, the blades may be withdrawn 30 within the casing for making the article safer in carrying around with a person or for shipment.

With the above and other objects in view, this invention consists of the construction, 35 combination, and arrangement of parts, all as hereinafter more fully described, claimed and illustrated in the accompanying drawings, wherein,

Figure 1 is a top plan view of the present 40 invention. Fig. 2 is a side elevation thereof. Fig. 3 is an end elevation thereof. Fig. 4 is a vertical section through the head of the instrument. Fig. 5 is a detail view of a cutting blade.

Throughout the following detail description and on the several figures of the drawings, similar parts are referred to by like reference characters.

In carrying out the present invention, a 50 body is provided comprising a shank or handle 1 and an enlarged portion or head 2, the latter being provided with a recess 3 arranged transversely with respect to the body. The head 2 is also provided with a

plurality of slots 4 which communicate with 55 the recess 3.

A blade holder or plate 5 is slidably mounted within the recess 3 and is provided with a plurality of threaded openings to receive the threaded shanks 6 carried by the 60 blades 7 for detachably mounting the latter on said blade holder. The cutting blades 7, which are illustrated as six in number but which may be any number desired, are adapted to operate and project through the 65 slots 4 and are provided with the rectangular shoulders 8 at the base of the blades. The head on the opposite sides of the recess 3 is provided with the recesses 9 which receive a cross member or bearing plate 10, the 70 latter being secured to the head by any suitable means, such as screws 11, to permit the removal of said plate 10. The plate 10 is provided with an opening in which is swiveled a threaded or screw member 12 which 75 carries on one terminal a thumb or knurled wheel 13 and on the threaded terminal receives the blade holder 5 for projecting or withdrawing the blades 7 as said member 12 is rotated.

The form of the blades 7 and the provision of the shoulder portions 8 are features of advantage of my instrument in that the blades, by passing through the slots 4, are practically interlocked with the head 2. As 85 the shoulder 8 of each blade is rectangular in form and of a length corresponding to the width of the recess 3, it will be apparent that the abutting relation of the ends of the shoulder 8 of each blade with the walls of 90 the recess 3 and the interlocking relation of the blades 7 with respect to the head prevent liability of any unscrewing movement of the shanks 6 of the blades when the parts of the device have once been assembled. As the 95 blades are frequently adjusted under actual conditions of use of the instrument, the desirability of preventing looseness or accidental displacement of the blades is obvious.

From the foregoing, it will be noted that 100 upon rotating the threaded member 12 in one direction, the blades 7 will be projected to any desired point and upon reversing the movement of said member 12, said blades and plate holder will be withdrawn from a 105 projected position entirely within the head 2. When the blades are entirely withdrawn the instrument may be safely carried within

the pocket. When it is desired to remove the blade holder 5, the cross member or plate 10 will be detached from the head 2 whereupon the removal of said plate is made possible.

Having thus fully described the invention, what is claimed as new is:—

1. A veterinary instrument comprising a longitudinally grooved head, a blade holder 10 plate movable within the groove of the head, blades spaced apart and having threaded connections with said blade holder plate, the head being formed with slots through which said blades extend, means to shift the 15 plate within the groove aforesaid to wholly withdraw the blades from said slots into the groove, and means intermediate the blades and head to prevent accidental unscrewing of the blades from their holder 20 plate when said blades are disengaged from the slots.

2. A veterinary instrument comprising a

handle having at one end thereof a transversely elongated head formed with a longitudinal recess and having a plurality of 25 slots communicating with said recess, a blade holder mounted in said recess, a plurality of blades, each having a threaded shank screwed into the blade holder and being formed with an approximately rectangular head, the ends of which abut with the walls of the recess aforesaid to prevent turning movement or looseness of the blade upon the holder, said blades projecting through the slots above mentioned, and a member 30 35 carried by the head and connected with the blade holder for adjusting the same in the recess of the head.

In testimony whereof I affix my signature in presence of two witnesses.

FELIX FRANCIS OGIER.
